CLAIM

I claim the ornamental design for a car battery-powered soldering tool, as shown and described.

DESCRIPTION

FIG. 1 is a perspective view of a car battery-powered soldering tool showing my new design;

FIG. 2 is a side elevational view thereof, the elevational view of the opposite side being a mirror image thereof;

FIG. 3 is a top plan view thereof;

FIG. 4 is a bottom plan thereof;

FIG. 5 is an end elevational view thereof; and,

FIG. 6 is an elevational view of the opposite end thereof.

1 Claim, 4 Drawing Sheets

FIG. 2.

FIG. 6.

FIG. 3.

FIG. 5.

FIG. 4.
